(57) **CLAIM**

The ornamental design for a vanity case, as shown and described.

DESCRIPTION

FIG. 1 is a top-front-left perspective view of a vanity case showing our new design;

FIG. 2 is a bottom-rear-right perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines, showing the plurality of ventilation apertures and grilles in FIGS. 2 and 8; the latches, drawer, control panel, and buttons in FIGS. 1 and 3; the hinges and power 25 socket in FIGS. 2 and 4; the filter slot, unitary switch, and input ports in FIGS. 1 and 5; and the perimetric band in FIGS. 1 through 8, illustrate portions of the vanity case and form no part of the claimed design.
